(57) **CLAIM**

The ornamental design for radiocommunication equipment,
as shown and described.

DESCRIPTION

FIG. 1 is a front view of the radiocommunication equipment
according to the present invention.

FIG. 2 is a perspective view of the radiocommunication
equipment according to present invention as seen from the
front, top and right side thereof.

FIG. 3 is a top view of the radiocommunication equipment
according to the present invention.

FIG. 4 is a bottom view of the radiocommunication equipment
according to the present invention.

FIG. 5 is a left side view of the radiocommunication
equipment according to the present invention.

FIG. 6 is a right view of the radiocommunication equipment
according to the present invention; and,

FIG. 7 is a back view of the radiocommunication equipment
according to the present invention.
